METAL VAPORIZING FURNACE

George Anderson, Hammond, Ind., and Rangwald S. Olsen, Chicago, Ill., assignors to International Smelting & Refining Company, New York, N. Y., a corporation of Montana

Application May 28, 1937, Serial No. 145,257

6 Claims. (Cl. 266—24)

Our invention aims to provide an improved furnace for the vaporizing more particularly of zinc, and a method of operation by which there is a lessening of the tendency to vaporize certain impurities which may be in the zinc.

5 The accompanying drawings illustrate an embodiment of the invention. Fig. 1 is a longitudinal vertical section along the line 1—1 of Fig. 3. Fig. 2 is a transverse vertical section along the line 2—2 of Fig. 1. Fig. 3 is an end elevation. Fig. 4 is an enlarged detail of Fig. 1.

The furnace illustrated is of a generally rectangular shape with a bottom 1, side walls 2 and end walls 3 built up of refractory material, which 15 can be either a high grade firebrick or a combination of firebrick and plastic insulating refractories. The method and materials used depend on the amount of heat calculated to be conducted through it to the monolithic container 20 or hearth, hereinafter referred to. The fact that molten zinc is hard to hold in a structure of refractory materials on account of the hydrostatic pressure has been taken into consideration and provided for by encasing the lower part 25 of the furnace, the part which carries the molten bath, in a steel shell comprising a bottom 4, sides 5 and ends 6. The furnace is braced on the bottom by any usual or suitable steel structure such as cross-beams 7 and longitudinal girders 8; at the sides by upright buckstays 9 and across the 30 top by tie rods 10. The top of the completed structure comprises an arch 11 of firebricks with a cover 12 of plastic insulation. On the bottom wall 1 of the complete structure is a hearth or container 13 for the molten charge of zinc or other metal. It is preferably a monolith with sides 14, Fig. 2, and ends 15, Fig. 1, of a height 35 sufficient to contain the molten bath. It may be of various refractory materials, such for example as silicon carbide.

Above the container or hearth is a horizontal roof 16. The space 17 above the roof 16 is a heating or combustion chamber. The heat therefrom is transmitted through the roof 16 to the 45 surface of the bath. The roof 16, therefore, is closely spaced above the bath and the outer cover 11 is sufficiently high to leave an abundant space 17 for combustion of the fuel. Burner openings are indicated at 18 and combustion gas outlets 19. Gas, oil or powdered coal may be used. At 50 20 are located openings for pyrometers so as to indicate and record the temperature within the heating chamber and to direct the control thereof as far as necessary.

The arch 12 illustrated is built of blocks of refractory material of high heat conductivity such, for example, as silicon carbide; the joints being made substantially vapor-tight by using a suitable refractory cement.

55 A stack 21 is located at one end of the struc-

ture, up which the vapor is drawn and burned to oxide or conducted to a chamber in which it is sublimed to zinc dust or condensed to cakes of solder, or treated in any usual or suitable way.

Through one of the end walls 3, there is an 5 opening 22 leading into the vaporizing chamber between the roof thereof and the upper edge of the hearth or container. It communicates through an opening 23 with the stack and also registers with a larger opening 24 in the outer 10 wall of the stack, the opening 24 being closed during operation. The opening 22 is the exit 15 for the vapors evolved in the container. It may also be used for the purpose of charging the zinc or other metal into the container. At the other 20 end, through the end wall 3, there are openings 25 of smaller size and designed chiefly for introducing any inert or reducing gas into the vaporizing chamber whenever this may be desired.

In ordinary operation these openings are 25 plugged with clay. When the introduction of such gases is not desired, the openings 25 can be used as exits for metal vapors or inlets for charging similarly to the opening 22 at the opposite end; and they may be made of the same 30 size as the opening 22 for that purpose, although here shown of smaller size. Of course, where the openings 25 are to be used as an exit for the vapor, they must be connected to a stack or other means for treating or utilizing the vapor.

At one side, and inclined downward from the bottom 13 of the container, is a tap hole 26 leading to a chute 27. It is normally plugged with clay or the like and is opened as necessary for the drainage of residual non-volatile metals 35 or for removal of molten charge. On the opposite side and leading downward into the top of the container is an opening 28 through the wall connecting with a vessel 29. This opening too is normally plugged. When the plug is withdrawn it may be used as a charging spout through 40 which molten metal is run into the furnace for treatment without access of oxidizing gases.

The roof 16 of the volatilizing chamber has 45 a vapor seal at its ends shown on a large scale in Fig. 4. There are recesses in the end walls 3 of the furnace structure. End bricks 30 of the roof extend into these recesses, where they are surrounded by a seal consisting of a mass of plastic refractory cement. This makes the joint 50 vapor-tight and still allows for some expansion and contraction of the roof in the lengthwise direction. In cross-section it is arch shaped as shown in Fig. 2.

In operating the furnace fuel is introduced and 55 burned in the combustion chamber 17. The refractory roof 16 of the vaporizing chamber is heated. Metal is introduced through the openings 22 or 25 or through the charging spout 28, 60

preferably through the charging spout when molten metal is used.

Heat transmitted through the arch or top 16, after first melting the charge if it shall have 5 been introduced in solid form, is radiated to the bath sufficiently to vaporize the latter. The vapors are then led away to be oxidized, condensed, sublimed or otherwise used.

The process of applying the heat to the surface only of the molten body of zinc minimizes the turbulence thereof. Any impurities in the bath of greater specific gravity than zinc such, for example, as lead and copper, tend to remain in the bottom of the bath and will be vaporized 15 to a less extent than if the heat were applied below and a more turbulent vaporizing operation maintained.

The improved furnace has several advantages over the type commonly used in zinc distillation, in which the zinc has been carried in cylindrical pots of ceramic material or large graphite bottles with a maximum capacity of about one ton of zinc. Such furnaces require frequent recharging, with attendant high labor cost. 20 They also involve great expense for the maintenance of the numerous pots.

The furnace of the present invention is not subject to any such limitation of size as the old furnaces, involves a smaller labor charge and 25 eliminates the old charge for replacement of pots or bottles.

The present furnace also is well designed for receiving a molten charge. Such charging on a large scale is simple and quick, resulting in gross- 35 free metal within the furnace chamber. Compared with a maximum of about one ton capacity for the older type, a furnace of this invention has operated satisfactorily with a charge of seven and one-half tons.

40 The arch 16 is much less expensive to maintain than the old structures. It bears no load. Its construction permits it to yield to changes in temperature and thus avoid breakage. The arch tends to seal itself since it is under pressure 45 of zinc vapor from the inside which tends to fill in all crevices with zinc vapor whenever such crevices may occur. Any small leaks that may occur through sudden cooling, permit passage of zinc vapors into the combustion chamber above 50 where they are oxidized. The leaks quickly disappear through formation of an oxide coating at the point of leakage. This keeps the volatilizing chamber air-tight at all times, which is essential to successful operation. Such vaporizing chambers are generally operated under vapor pressure 55 in order to prevent the entrance of air.

The large amount of zinc vaporized in one vessel permits of better control than in the case of small pots provided with a number of openings.

60 Continuous operation can be effected by introducing a constant stream of molten metal through the port opening 28 at such a rate as to compensate for the rate of vapor discharge through the opening 22. Any non-volatile metals 65 remaining behind in the chamber 10 can be tapped out through the tap holes 26; so that there is no difficulty in treating charges of zinc containing metal impurities.

70 Various modifications in the design and operation of the furnace may be made by those skilled in the art without departing from the invention as defined in the following claims.

What we claim is—

1. A metal vaporizing furnace which comprises

a monolithic container for molten metal, a furnace structure having a bottom and side and end walls supporting and enclosing said container and having a roof and a partition arch sprung from the sides and sealed to the end walls of said 5 furnace to provide a combustion chamber thereabove and a vaporizing chamber therebelow.

2. A metal vaporizing furnace which comprises a hearth for holding molten metal, a furnace structure having a bottom and side and end walls 10 supporting and enclosing said hearth, an arch sprung from the side walls of said furnace and extending to the end walls and having a layer of sealing bricks closely overlapping the ends of said arch and cemented into the end wall of said 15 furnace.

3. A metal vaporizing furnace which comprises a metal holding hearth having upturned side and end walls to hold molten metal, a furnace structure having a bottom and side and end walls supporting and enclosing said hearth, an arch sprung from the side walls of said furnace and sealed to the end walls thereof to provide a combustion-chamber above said arch and a vaporizing chamber therebelow and a metal shell 25 enclosing the bottom of said furnace and the side walls thereof to the level of said hearth.

4. A metal vaporizing furnace which comprises a metal holding hearth having a bottom and upturned sides and ends to contain molten metal 30 enclosed in the walls of said furnace and a furnace structure of metal having a bottom and side and end walls supporting and enclosing the bottom, side and end walls of said furnace to approximately the height of said hearth walls, a 35 roof spaced above said metal holding hearth and a partition arch sprung from the side walls of said furnace between said hearth and said roof and sealed to the end walls thereof to provide a heating chamber thereabove and a vaporizing 40 chamber therebelow.

5. A metal vaporizing furnace which comprises an outer shell of material impervious to metal and having a bottom, side and end walls, a furnace structure having a bottom, side and end walls 45 enclosed by the bottom, side and end walls respectively of said shell and having a bottom lining with upwardly extending side and end walls to form a metal holding hearth in the lower part of said furnace, said furnace having a roof and 50 a partition arch between said roof and said hearth sprung from the side walls of said furnace and sealed to the end walls thereof to enclose a vaporizing space above said hearth and a separate combustion chamber between said arch and said 55 roof.

6. A metal vaporizing furnace which comprises an outer shell of material impervious to metal and having a bottom, side and end walls, a furnace structure having a bottom, side and end walls enclosed by the bottom, side and end walls respectively of said shell and having a bottom lining with upwardly extending side and end walls to form a metal holding hearth in the lower part of said furnace, said furnace having a roof and 60 a partition arch between said roof and said hearth sprung from the side walls of said furnace and sealed to the end walls thereof to enclose a vaporizing space above said hearth and a separate combustion chamber between said arch and said 65 roof, means to supply metal to said hearth and means to remove metal vapors therefrom.

GEORGE ANDERSON.
